UNITED STATES PATENT OFFICE.

CHARLES J. DIEGES, OF BROOKLYN, NEW YORK, ASSIGNOR TO DIEGES & CLUST, OF NEW YORK, N. Y., A CORPORATION OF NEW YORK.

DESIGN FOR A RING.

Application filed September 24, 1924. Serial No. 10,894. Term of patent 7 years.

To all whom it may concern:

Be it known that I, CHARLES J. DIEGES, a citizen of the United States, residing in the borough of Brooklyn, county of Kings, and State of New York, have invented a new, original, and ornamental Design for a Ring, of which the following is a specification, reference being had to the accompanying drawing, forming a part thereof.

In the drawings,

Figure 1, is a top plan view of my new design; Figs. 2 and 3, side elevations of opposite sides of my new ring.

What I claim is:

The ornamental design for a ring, as shown.

CHARLES J. DIEGES.
